COMBINED FRUIT PEELER AND KNIFE OR THE LIKE

Charles P. Schiller, Winter Haven, Fla.

Application March 29, 1954, Serial No. 29,720

Term of patent 14 years

(Cl. D22—3)

To all whom it may concern:

Be it known that I, Charles P. Schiller, a citizen of the United States, residing at Winter Haven, in the State of Florida, have invented a new, original, and ornamental Design for a Combined Fruit Peeler and Knife or the like, of which the following is a specification, reference being had to the accompanying drawing, forming a part thereof.

I claim:

The ornamental design for a combined fruit peeler and knife or the like, as shown.
